UNITED STATES PATENT OFFICE.

DANIEL SULLIVAN, OF SPARTA, WISCONSIN.

RAILROAD-SWITCH CHAIR.

SPECIFICATION forming part of Letters Patent No. 317,042, dated May 5, 1885.

Application filed May 17, 1884. (No model.)

To all whom it may concern:

Be it known that I, DANIEL SULLIVAN, a citizen of the United States, residing at Sparta, in the county of Monroe and State of Wisconsin, have invented a new and useful Railroad-Switch Chair, of which the following is a specification.

My invention has for its objects, first, the substitution of one continuous chair for the two now in use; second, to decrease the liability of the breaking separate cast-iron chairs by the substitution of a continuous chair from rail to rail; third, to thereby maintain more perfectly the level of both rails, and thereby decrease the jar consequent upon any unevenness; fourth, to facilitate the "throwing" of the movable rail; fifth, its increased adaptability to any number of side tracks. I attain these objects by the mechanism illustrated in the accompanying drawings, in which—

Figure 1 represents a three-throw switch with continuous chair, as seen from above; Fig. 2, a side view of the same, showing the construction of the chair.

Similar letters refer to similar parts throughout the views.

In Fig. 1, A A A represent the chair. It is made by firmly mounting upon the switch-tie three rails, ten feet in length, (dividing a thirty-foot rail into three equal parts,) in such manner as is represented in cross-section in Fig. 2, A A. I thus secure a firm flat surface, ten feet long and eight inches in width, upon which rails F G H and F' G' H' firmly rest, and switch-rails D' D' can be easily made to slide by moving switch-bar E E. The chair is spiked to the switch-tie B B', and is held together by bolts c c, &c., making it a solid mass.

On the outer sides of the outer rails are fastened splices I I' by the bolts J J', which pass through the ends of the immovable rails, and

by means of washers maintain the required distances between these rails. The splices I and I' are to insure against accidental over-sliding of the movable rails. The pressure of 45 rails F G H F' G' H' rests upon rail No. 1 of the chair, and partly on the inverted rail No. 2. The movable rails D and D' rest upon rail No. 3 of the chair, and partly on inverted rail No. 2. Thus my invention is adapted to a 50 switch of any number of throws without increasing the liability of breaking.

In the chairs now in use the wear of the movable rail causes frequent breaking.

In Fig. 2, B is switch-tie; A A A, transverse section of chair, showing relative position of the three rails. c is bolt fastening three rails; I, plate on outer rail; J, end of bolt fastening immovable rails. In combination with the continuous switch-chair formed of 60 the two outer and the intermediate inverted rail-sections there must be a sleeper supporting said chair, depressed and located on a plane below the adjacent track ties or sleeper.

What I claim as my invention, and desire 65 Letters Patent for, is—

1. The herein-described continuous chair for railway-switches, consisting of the two outer lengths and the intermediate inverted length of railway-iron secured together by any 70 suitable means, substantially as set forth.

2. In combination with the continuous switch-chair formed of the two outer and the intermediate inverted rail-sections, the depressed sleeper supporting said chair, said 75 sleeper being located on a plane below the adjacent track ties or sleeper, all substantially as set forth.

DANIEL SULLIVAN.
